FLAT GARTER GRIP

Joseph Jacobs, Bridgeport, Conn., assignor to
 A. J. Donahue Corporation, Milford, Conn., a
 corporation of Connecticut

Application April 27, 1934, Serial No. 722,693

8 Claims. (Cl. 24—248)

This invention relates to garters and more particularly to a flat garter clasp or grip for supporting a garment without projecting bulges or buttons.

5 One object of this invention is to provide a garter grip of the above nature which consists of only two parts, and may be conveniently made from flat metal stampings without complicated forming and assembly operations.

10 A further object is to provide a garter grip of the above nature which will be simple in construction, inexpensive to manufacture, easy to assemble and manipulate, compact, ornamental in appearance, and very efficient and durable in use.

15 With these and other objects in view, there have been illustrated on the accompanying drawing two forms in which the invention may be conveniently embodied in practice.

In the drawing:

20 Fig. 1 represents a perspective view of the garter grip embodying the invention, as it appears in use.

Fig. 2 is an enlarged perspective view of the garter grip detached from the supporting strap.

25 Fig. 3 is a front elevation of the same.

Fig. 4 is a side view of the same.

Fig. 5 is a vertical sectional view of the same as it appears when attached to the strap and supported garment.

30 Fig. 6 is a front elevation view of a modified form of garter grip.

Referring now to the drawing in which like reference numerals denote corresponding parts throughout the several views, the numeral 10 indicates generally a garter grip comprising two members, to wit: a flat metal body frame 11, and a hinging T-shaped tongue member 12. The body frame 11, as best shown in Figs. 2 and 3, consists of a lower pear-shaped open loop 13 provided with a pair of intermediate inwardly extending opposed ears 14 and 15 positioned in such a manner as to form a substantially key-hole shaped opening 16, the upper part of which is formed in the shape of a horizontal ellipse and merges into a lower semi-circular opening.

The upper end of the frame 11 is provided with a pair of cross bars 17 and 18 between which is a transverse slot 19 for receiving the looped elastic garter strap 20.

35 The T-shaped tongue member 12 comprises an intermediate longitudinal shank 21 terminating at its lower end in an integral circular head 22 and formed at its upper end with an integral transverse loop 23 having a longitudinal slot 24 therein. The slot 24 is adapted to substantially align with the slot 19 when the garter is in closed position, and the upper cross bar 24a of the tongue loop 23 is adapted to be embraced by an elongated tubular hinge barrel 25 bent over from the upper edge of the upper cross bar 17 of the

body frame 11, thus permitting the tongue member 12 to swing freely relative to the body frame 11.

The hinge barrel 25 is preferably offset forwardly of the plane of the body frame 11 to avoid inwardly projecting parts which might cause discomfort to the wearer.

30 The garter strap 20 is adapted to be attached to any suitable supporting means such as a girdle (not shown). The strap 20 is adapted to be inserted through both slots 19 and 24 of the frame and tongue respectively, and the looped strap 20 surrounds and conceals the hinge barrel 25.

35 The circular head 22 and the adjacent portion of the shank 21 of the tongue member 12 are preferably enclosed in a tight fitting rubber jacket 26, which may be readily applied by means of one or more coats of liquid vulcanized latex and allowed to dry thereon.

40 In attaching the garter to a garment, such as a stocking 27, the tongue member 12 will first be swung outwardly to a position such as shown in Fig. 2, so as to clear the key hole opening 16. The upper edge of the stocking 27 will then be formed in a loop 28 and drawn through the opening 16 sufficiently far to permit the head 22 of the tongue 12 to be swung down into the stocking loop back to its normal position. At this time the stocking loop will be drawn flat across the front face of the head 22. As best shown in Fig. 5 a portion of the stocking will then be embraced between that part of the circular tongue head 22 which overlaps the lower portion of the pear shaped loop 13, causing the adjacent portion of the stocking to be formed in a double reverse loop. By means of the above construction it will be seen that the greater the pull on the stocking, the stronger will be the clamping action of the garter upon the edge of the stocking.

45 It will be understood that the opposed inner ears 14 and 15 on the loop 12 will cause the edge of the garment to embrace a greater portion of the periphery of the circular head 22 and thus to increase the clamping grip upon the edge of the garment.

Moreover, by reason of the rubber jacket 26 upon the tongue head 22, it will be difficult for the stocking to slip out from underneath said head 22.

Modified form

50 In the modified form of the invention illustrated in Fig. 6 a body frame 29 is shown comprising a lower pear-shaped loop 30 and an integral upper transverse loop 31, said frame 29 being identical in all respects to the frame in the first form shown in Figs. 1 to 5 except that the hinge barrel 25 is omitted from the top of the loop 31. The intermediate bar 32, between the lower and upper loops 30 and 31 respectively, is provided with a reduced section 33 to which is 55

hingedly connected a tongue member 34 by means of an eye loop or barrel 35 formed at the upper end of said tongue 34 and adapted to embrace said reduced section 33.

5. While there have been disclosed in this specification several forms in which the invention may be embodied, it is to be understood that these forms are shown for the purpose of illustration only, and that the invention is not to be limited 10 to the specific disclosures but may be modified and embodied in various other forms without departing from its spirit. In short, the invention includes all the modifications and embodiments coming within the scope of the following claims.
15. Having thus fully described the invention, what is claimed as new, and for which it is desired to secure Letters Patent, is:

1. In a garter grip, a one-piece frame having an opening therein which is large enough to permit a loop in the top end of a stocking to be drawn therethrough, and a rigid tongue member hingedly connected directly to the upper end of said frame and adapted to swing away from the plane of said frame, said tongue member being adapted to press said stocking tightly against said frame for holding it securely in detachable position, said tongue member lying at all times at one side of said frame.
2. In a garter grip, a one-piece frame having a lower key-hole shaped slot and an upper transverse slot spaced therefrom, a rigid tongue member pivotally connected directly to said frame, and a head formed at the distal end of said tongue, said head being adapted to span the lower reduced portion of said key-hole slot and overlap the adjacent portion of said frame, for holding a garment securely in position, said tongue member lying at all times at one side of said frame.
3. In a garter grip, a one-piece frame having a lower key-hole shaped slot and an upper transverse slot spaced therefrom, a rigid tongue member pivotally connected directly to said frame, and a head formed at the distal end of said tongue and having a rubber jacket, said head being adapted to span the lower reduced portion of said key-hole slot and overlap the adjacent portion of said frame, for holding a garment securely in position, said tongue member lying at all times at one side of said frame.
4. In a garter grip, an open flat one-piece metal frame having a lower key-hole slot and an upper transverse loop, a hinge barrel formed along the upper edge of said loop, a tongue member having

a transverse loop for direct pivotal engagement within said barrel, said tongue member having an enlarged head formed at the distal end thereof, said head being adapted to span the lower reduced section of said slot and overlie the adjacent portion of the frame surrounding said lower slot, said head being adapted to receive a loop of a garment passed up through said key-hole slot, and the tension of said garment serving to hold said head flat against said frame to cause said head and frame 10 to clamp together on the edge of said garment.

5. In a garter grip, an open one-piece metal frame comprising a lower pear-shaped loop and an upper integral transverse elongated loop, a rigid tongue member having a transverse elongated 15 loop pivotally connected directly to the upper end of the loop of said frame, the lower end of said tongue being adapted to receive a loop in the edge of a garment and serving to clamp said edge against said frame when tension is applied to said 20 garment, said tongue member lying at all times at one side of said frame.

6. In a garter buckle, a sheet metal one-piece frame having a transverse strap-embracing cross bar and an intermediate cross bar, a rigid tongue 25 member having direct pivotal connection with said intermediate cross bar, the lower end of said tongue member having an enlarged head adapted to receive the looped edge of a garment, and serving to clamp said edge against said frame when 30 said garment is under tension, said tongue member lying at all times at one side of said frame.

7. In a garter grip, an open metal one-piece frame having a straight upper cross bar, a rigid slotted tongue member having an upper cross bar 35 adapted to be brought adjacent the cross bar of said frame, a garment supported strap passing around said cross bars, the lower end of said tongue member being adapted to receive the looped edge of a garment and serving to clamp said 40 edge against said frame when tension is applied to said garment, said tongue member lying at all times at one side of said frame.

8. In a garter buckle, an open metal one-piece frame having an upper cross bar for receiving a 45 supported strap, a tongue member pivotally supported with respect to said frame and having an enlarged head on its lower end, the opposite edges of the lower end of said open metal frame having inwardly extending ears to cooperate with said 50 head for clamping upon the looped edge of a garment to be detachably supported thereby.

JOSEPH JACOBS.
